Fig. 8.

UNITED STATES PATENT OFFICE.

OSCAR WIEDERHOLD, OF PHILADELPHIA, PENNSYLVANIA.

HEATER.

Application filed January 31, 1922. Serial No. 533,076.

To all whom it may concern:

Be it known that I, OSCAR WIEDERHOLD, a citizen of the United States, and resident of Philadelphia, in the county of Philadelphia and State of Pennsylvania, have invented certain new and useful Improvements in Heaters, of which the following is a specification.

This invention relates to heaters of the kind in which gas or vapors, such as the vapors of gasoline, kerosene, or the like, are used as fuel to produce heat. It is the object of this invention to provide a heater of this character which can be operated with a high degree of efficiency, and at the same time with a low fuel consumption, and in which there will be perfect combustion of the fuel. Another object of this invention is to provide means for preheating the fuel, thus increasing the heating effect. Still another object is to devise an apparatus to which liquid fuel, such as kerosene, gasoline and the like is fed, which liquid fuel is vaporized before it reaches the burners.

These objects and the advantages of my invention will appear fully from the description following hereinafter, and the novelty will then be pointed out in the appended claims.

Reference is to be had to the accompanying drawings, in which I have shown as examples several embodiments of my invention, as well as several different ways of using the same. In these drawings,

Fig. 1 is a longitudinal cross section through one form of heater unit taken on line 1—1 of Fig. 2, the latter being a face view of the heater unit shown in Fig. 1; Fig. 3 is transverse section taken on line 3—3 of Fig. 1; Figs. 4 and 5 illustrate a heater in which several units shown in Figs. 1 to 3 are arranged side by side, Fig. 4 being a front elevation and Fig. 5 a section on line 5—5 of Fig. 4; Figs. 6 and 7 illustrate a different form of heater, the former being a vertical section on line 6—6 of Fig. 7 and the latter a partial horizontal section on line 7—7 of Fig. 6; and Fig. 8 is a section similar to Fig. 1, but illustrating a form of my invention in which liquid fuel may be used.

The form of my invention illustrated by Figs. 1 to 3 comprises a rectangular box 10 enclosing a mixing chamber 11 into which leads a fuel supply pipe which may be a

Bunsen tube 12, as shown. The upper wall 13 of the box 10 is provided with a number of outlets in the form of burner tips 14 which, in the particular example shown, are staggered so as to form rows of three and two tips alternating with one another. Arranged above the box 10 and spaced therefrom by means of short posts 15 is a rectangular frame 16 having a narrow flange 17 serving to support a heating plate 18 made of magnesia or other refractory material and provided with holes 19 each in alignment with one of the burner tips 14. Supported on the plate 18, within the frame 17, is another plate 20 also made of refractory material and having, in the particular example shown, transverse openings 21 of rectangular shape, the two outer ones of which are located above solid portions of the plate 18, while the openings 21 between these two outer openings lie above, and in registry with, those holes 19 of the plate 18 which are in line with the burner rows having two tips. Above the rows of openings 19 corresponding to the three-tip burner rows are located ribs 22 of the plate 20, which ribs are formed by the portions of the plate 20 which lie between adjacent openings 21 of said plate. The ribs 22, however, do not cover up these openings 19 entirely, but they are spaced from the upper surface of the plate 18, as shown at 23 (Fig. 1), and serve to deflect the flame issuing through the particular openings 19 above which they are located.

The operation of the device illustrated in Figs. 1 to 3 is as follows: Gaseous fuel is supplied through the Bunsen tube 12 to the mixing chamber 11 where it is thoroughly mixed with the air which it has drawn in through the air openings 24 in said tube. This combustible mixture then passes through the openings in the burner tips and is ignited on issuing through said tips, say by means of a match, generally applied to the outlet of one or more openings 21. The fuel and air mixture passing through those burners which are in line with the openings 21 in the plate 20, will burn in a straight, unobstructed flame, while that passing through the other rows of openings, that is, through those in line with the ribs 22, will be deflected to both sides by the lower surface of the ribs and compelled to travel around such ribs and in close contact therewith.

Both the heating plate 18 and the deflecting plate 20 will thus be thoroughly heated and the plate 18 as well as the portions of the plate 20 surrounding the openings 21 will be brought to a high degree of incandescence. Additional air to support combustion is admitted through the space (see Figs. 1 to 3) provided between the box 10 and the heating plate 18 and a thorough combustion of the fuel is thus insured. Those flames which pass through the plates 18 and 20 unobstructed, provide the necessary draft for the other, deflected flames.

The fuel passing through the mixing chamber 11 is preheated in said chamber by the heat deflected downward from the heating plate 18. Even if the air supply hole 24 in the pipe 12 should be clogged up or otherwise closed, partly or entirely, the air supplied at the burner tips 14 would be sufficient to produce a Bunsen flame, although the combustion would not be so efficient. The two plates 18, 20 need not be separate plates, but might be made, if desired, to form an integral heating body.

The heater unit illustrated in Figs. 1 to 3 may be used either alone for heating or cooking purposes, or a number of them might be utilized in a gas range. A convenient form 30 has been illustrated in Figs. 4 and 5, in which three heater units 25 have been shown arranged side by side in a heater 26 of suitable construction. Gas or other fuel is supplied to the heater units through a common 35 Bunsen tube 27 and a T-connection 28. The walls of the heater are preferably made of an asbestos mixture containing a red pigment and, as shown in Fig. 5, the heater units are preferably so arranged in one of 40 said walls that the flanges 17 of the frames 16 are flush with the rear face of the said wall, so that the air intake for the additional air is located behind said wall. The red walls of the heater 26 will strongly reflect 45 the heat radiated from the heater units 25 and a very effective heating action is thus obtained. Figs. 4 and 5 show lines in imitation of brick work; this effect may be obtained by painting white lines on the 50 faces of the red walls, to indicate the mortar in the joints.

While the heater illustrated in Figs. 4 and 5 will generally be used with its back facing a wall of a room, or in connection with an 55 open fireplace, I have shown in Figs. 6 and 7 a form of heater which radiates heat in all directions and can therefore be used conveniently in the center of a room. The relative arrangement of mixing chamber, heating and deflecting plates is the same as in the form of my invention shown in Figs. 1 to 3; they differ, however, in shape. Supported on legs 29 in a base plate 30, provided in the center with a circular opening 60 and carrying an annular box 31 containing

the mixing chamber 32 into which leads the fuel-supply tube 33 having air-inlets 33'. In the top wall of the box 31 are located the burner tips 34 which in this particular case are arranged in radially-extending rows 70 having alternately two and three tips. The opening 35 formed in the center of the base plate 30 and the box 31 serves to supply to the burners an additional amount of air to support combustion. Above the box 31 is 75 supported, at a distance therefrom, an annular frame 36 carrying a heating plate 37 and a deflecting plate 38, the plate 37 having circular openings 39 registering with the burner tips 34, while the deflecting plate 38 80 has oblong openings 40 leaving between them ribs which cover up, to a certain extent, alternate rows of openings 39 (and burner tips 34). Supported at the center of the plate 38 is a cone-shaped inverted radiating member or body 41 made of magnesia or other refractory material; and surrounding this member and the frame 36 is a cylindrical screen 42 provided with suitable openings 43 and carried on the base plate 30, the latter being provided with a vertically-extending flange 44 surrounding the lower end of the screen 42. The open end of the member 41 is closed by a cover 45, and underneath the opening 35 is arranged a bracket 46, the cover 45 and bracket 46 being connected by a rod 47 which holds the whole structure together. The units 48 at the lower end of the rod 47 also serve to hold in place underneath the opening 35 a fire pan 100 49 which, while not preventing the air from entering the opening 35, will catch any material which may become detached from the heating plate 37 during use of the heater.

The operation of the heater just described 105 is the same as with the other forms of my invention, except that the heat of the flames will also be communicated to the conical radiating member 41 which will be brought to incandescence, at least in part, and will 110 radiate its heat all around.

In Fig. 8 I have illustrated a form of burner unit similar in its general features to the form shown in Figs. 1 to 3, but in which liquid fuel, such as kerosene, oil and the like may be fed to the apparatus and vaporized therein before being ignited. According to Fig. 8, I provide a box 50 containing two chambers, a lower or mixing chamber 51 and an upper or vaporizing chamber 52. Into the chamber 52 leads a fuel-supply pipe 53 provided with a suitable valve 54, and from the upper space of this chamber leads into the lower or mixing chamber 51 a pipe 55, which may be in 120 the form of a Bunsen tube, so as to admit air. The chamber 51 communicates with the space above the chamber 52 by a number of passages 56 which at their upper ends 125 form burner tips 57. At its upper edges the 130

box 50 is provided with upwardly-extending flanges 58 forming with the upper surface of the box a pan 59 into which alcohol or the like may be poured to start the operation of the heater. Supported on the box 50 and spaced from the flanges 58 for the purpose of admitting air, is a rectangular frame 59 (similar to the frame 16 of Figs. 1 to 3) carrying a heating plate 60 and a deflecting plate 61 constructed like those described in connection with Figs. 1 to 3.

The operation of this device will be readily understood: Liquid fuel, such as for instance kerosene, is admitted to the chamber 52 by opening the cock or valve 54. Then alcohol or the like is poured into the pan 59 and ignited, thereby heating the upper wall of the chamber 52 and vaporizing the fuel contained in said chamber. The vapors thus produced are forced through Bunsen tube 55 into chamber 51 where they are thoroughly mixed with the air drawn in through the openings in said tube. This fuel-and-air mixture then travels through the passages 56, is ignited on issuing from the burners 57, and produces heat in the same manner as described in connection with Figs. 1 to 3. After the operation has thus been started, the liquid fuel will continue to be vaporized by the heat radiated downwardly from the burning fuel.

I claim:

1. In a heater, a heating body having perforations, and also having solid portions located in registry with the outlets of said perforations but spaced therefrom so as to allow gases issuing from said outlets to escape laterally from the space between the said solid portions and said outlets, and burners having outlets in line with said perforations on the inlet side thereof and in such proximity to said inlets as to cause a supply of air to be drawn into said perforations together

with the combustion gases issuing from the burner outlets.

2. In a heater, a heating body having perforations and also having solid portions between said perforations and additional solid portions located in registry with the outlets of said perforations but spaced therefrom so as to allow gases issuing from said outlets to pass laterally from the space between said additional solid portions and said outlets, and slot-like openings located between said additional solid portions, and burners having outlets in line with said perforations on the inlet side thereof.

3. In a heater, a burner having a Bunsen arrangement and provided with outlets, and a heating body spaced from the outlets of said burners but adjacent thereto, said body having, on the side facing the burner, openings in registry with burner outlets, and, on the side distant from the burner outlets, ribs in line with the outlets of said openings and spaced therefrom so that the combustion products from the burner outlets will travel in a straight line to and through said openings of the heating body, then laterally between said ribs and the outlets of said openings, and finally out through the spaces between said ribs.

4. In a heater, a heating body having holes and solid strips located in line with said holes in front of their outlets, at a distance therefrom, and a burner to direct a Bunsen flame into said holes, whereby the Bunsen flame striking said solid strips will be deflected laterally and back on the solid portion of the heating body between such strips, to bring such solid portion to incandescence.

In testimony whereof I have signed this specification.

OSCAR WIEDERHOLD.
